(57) **CLAIM**

The ornamental design for a bidet attachment, as shown and described.

DESCRIPTION

FIG. 1 is a perspective view of the bidet attachment showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the bidet attachment is being used.

The broken lines shown in the drawings represent portions of the bidet attachment that form no part of the claimed design.
